UNITED STATES PATENT OFFICE.

MOSES C. NIXON, OF CHICAGO, ILLINOIS.

SELF-ALIGNING BALL BEARING.

Original application filed January 3, 1921, Serial No. 434,754. Divided and this application filed December 15, 1922. Serial No. 607,241.

This application is a division of my former application Serial No. 434,754, filed January 3, 1921, in which the lubricating means shown and described therein is omitted in the present case.

The objects of the present invention are to provide means that will permit self alignment of rolling contact bearings when placed between thrust and resisting members, and such other improvements as may hereinafter appear, and consists, preferably, in the construction described, which may be varied without departing from the spirit of my invention.

15 In the drawings Figure 1 is a side elevation of a windmill, with the side of the covering cut away to better show the interior, and the top broken away to reduce the size of the drawing; Fig. 2 is a plan view 20 of Fig. 1, in which the invention is shown in connection with the wind-wheel shaft; Fig. 3 is an enlarged view of the invention in connection with a section of the windmill, and Fig. 4 is a modification, illustrating the invention as applied at either or 25 both sides of the bearing.

Referring to the drawings, similar numerals of reference indicate corresponding parts in the different views, in which 1 is an incasement, which in the present case, forms the main or supporting frame, and 2 is a covering for the same.

To simplify the incasement or main-frame, supports 5 are made separately and secured thereto, as by bolts 6, and to furnish better foundation for these supports, ribs 7 that rise above the surface of extension bottom of the incasement are provided.

Secured to the main-frame, as by bolts 40 10, are journal boxes 11, and journaled therein is a wind-wheel or driving shaft 12, to which are rigidly secured gear-pinions 13. These pinions mesh with and drive gear-wheels 14, which, in the present case, 45 are preferably mounted upon stud-shafts 15. These stud-shafts are provided with heads 15' to retain the gear-wheels in place, and are rigidly held by and extend from boxes or anchors 16, which in turn are rigidly 50 secured to the main-frame, as by bolts 17.

Mounted in the supports 5 is a shaft 33, which may be secured in any suitable manner, and pivotally mounted thereon is a frame or member 34. The sides at the free 55 end of this frame are firmly connected, as

by connection 41, and pivotally mounted in hubs 43, 43' is a shaft 42, upon which is mounted and firmly secured hub 44 of the pitman 45, in any suitable manner. The other end of the pitman being loosely 60 mounted upon a wrist-pin 47 that extends across and forms an operative connection with the gear-wheels 14, and is operated thereby. Also, near the free end of the pivoted frame, a shaft 54 is pivotally mounted 65 in hubs or bearings 55, 55', and firmly secured thereto, in any suitable manner, is the hub 56 of the pump-rod, into which is tapped the pump-rod 56', the latter being operative through the tubular mast 59. 70

These various parts have been more minutely described and explained in the previously mentioned application.

The friction caused by the end thrust of the wind-wheel or driving shaft consumes 75 a great deal of power, and to avoid or reduce this friction an end thrust rolling contact bearing has been devised, in which cup 26, cone 27 and balls 28 may be used in connection with an inverted dish or convex 80 shaped member 29 to compensate for unevenness of the resisting surface 30, thereby permitting adjustment and self alignment of the bearing, whereby a more uniform pressure is distributed on the balls. In the 85 application of this end thrust bearing, in the present case, the end of shaft 12 is reduced thereby forming a shoulder 31, the end passing through the aperture of the convex member, with the shoulder 31 resting 90 against the bearing.

When the device is used in connection with a thrust bearing only, the cup and cone may be enlarged (see Fig. 3), giving more room between the cone and shaft thereby affording 95 greater adjustment of the convex member, in which case the opening through the web of the cup 26 should be of a size approximately that of the shaft, so as to hold the bearing in a correct position. 100

The modification shown in Fig. 4, illustrates a combination self aligning radial and thrust rolling contact bearing, in which the present invention may be applied at either or both sides of the bearing, depending 105 upon whether the thrust and resisting member presents a true or rough contact surface. In it, the size of the cup 26' and cone 27' should be such that the latter will contact with the shaft 12' and revolve therewith. 110

In this construction it is necessary that the cone be short enough to avoid interfering with the convex member as it moves toward the shaft, and the convex member 29^a is shown in contact with an even surface of pinion 13^a and the other convex member 29^b is supported by the journal box 11^a, which is shown with a rough contact surface in the form of a lump 11^c, and illustrates adjustment permitted in connection with a combination bearing.

It is evident that this invention is adapted to other purposes than in connection with windmills, and it is not the intention to limit its use to that purpose. Also, while its preferred embodiment has been described herein I do not wish to be limited to the details of construction shown, as it is apparent changes may readily be made without departing from the spirit of my invention; and having described one form of construction I claim as new and desire to secure by Letters Patent the following:

1. In a mechanism, the combination of a revoluble shaft, a member rigid with and carried by said shaft, a resisting member, a rolling contact bearing on said shaft and between said members, and a compensating device mounted between one of said members and the bearing and having a convex surface adapted to seat against the bearing in different angular positions when being assembled.

2. In a mechanism, the combination of a revoluble shaft, a member rigid with and

carried by said shaft, a resisting member, a self contained rolling contact bearing on said shaft and between said members, and a compensating device mounted between one of said members and the bearing and when being assembled is free to move to different angular positions independent of both, and having a convex surface adapted to seat against the bearing.

3. In a mechanism, the combination of a revoluble shaft having a projection associated therewith, a rolling contact bearing in contact with said projection, a resisting member, and a compensating device mounted between the resisting member and said bearing and adapted to seat against the latter in different angular positions, while being assembled.

4. In a mechanism, the combination of a rotatable end thrust member, a rolling contact bearing, a resisting member, and a compensating device mounted between one of said members and the bearing and free to move when being assembled to different angular positions and having a convex surface adapted to seat against the bearing.

5. In a mechanism, the combination of a rotatable end thrust member, a rolling contact bearing, a resisting member, and a compensating device mounted between one of said members and the bearing and free to move when being assembled to different angular positions and adapted to seat against the bearing.

MOSES C. NIXON.
